M. HERSKOVITZ

ILLUMINATED ORNAMENTAL DEVICE

Filed Dec. 10, 1923

Inventor.

Max Herxovitz
By Deyunforn, Lee, Britton & Wilcox
Att'd Sosa

UNITED STATES PATENT OFFICE.

MAX HERSKOVITZ, OF CHICAGO, ILLINOIS; WILLIAM HERSKOVITZ AND CHARLES WEINFELD EXECUTORS OF SAID MAX HERSKOVITZ, DECEASED; SAID WILLIAM HERSKOVITZ NOW BY JUDICIAL CHANGE OF NAME WILLIAM HERST.

ILLUMINATED ORNAMENTAL DEVICE.

Application filed December 10, 1923. Serial No. 679,842.

My invention relates, more particularly, though not exclusively, to electrically-lighted wreath devices, as for example, and more particularly, Christmas wreaths and 5 Easter decorations; and my object is to provide a novel, simple, strong, and inexpensive construction of such device which will present a very pleasing appearance.

Referring to the accompanying drawings: 10 Figure 1 is a face view of one of the forms in which my improved device may be provided, a portion of the ornamental covering material for the wreath proper, broken away, to disclose the core-member of the 15 device. Figure 2 is an enlarged face view of the lower, clip-equipped, portion of the device, with the decorative covering omitted. Figure 3 is a section taken at the line 3 on Fig. 2 and viewed in the direction of 20 the arrow; and Figure 4, a cross-sectional view of another of the many forms in which my invention may be embodied. Referring particularly to the construction shown in Figs. 1, 2 and 3 it comprises a core 4 25 preferably formed of sheet fibrous material, as for example, card board or paper board, this core being in the form of an annulus of concavo-convex cross-section, the convex portion being at the front face of the device to 30 cause the latter to present a rounded front surface. The core 4 carries, at its lower portion, an electric-lamp-socket-supporting 35 clip 5 shown as formed of a sheet metal strip extending across the front, convex, surface of the core 4. The clip is secured in place on the core by bending the upper and lower ends of the strip backwardly and downwardly and upwardly, respectively, to 40 overlap the rear side of the core, as represented at 6 and 7. The upper portion of the clip 5 is formed with the substantially flat portion 8 which, when the clip is assembled with the core, as shown, extends substantially horizontal. The flat portion 45 8 has secured thereto, an upwardly extending hollow nipple 9 threaded at its upper extremity and forming a support for an electric-light-supporting socket device 10, which may be of any desirable construction 50 and which is preferably of the so-called candle socket type affording the outer candle-simulating tube 11. The socket device 10 is supported on the nipple 9, at the lower ring portion 12 of the device 10 which is

apertured and internally threaded to adapt 55 it to be screwed upon the upper, threaded end of the nipple 9. The nipple 9 may be secured to the clip 5 in any desirable way, as for example, by providing the lower end of the nipple 9 of reduced diameter at which 60 portion it extends through an aperture (not shown) in the flat portion 8 of the clip, to extend below the latter, the nipple seating at its annular shoulder 13 upon the upper surface of the portion 8 and the lower extremity of its reduced portion being bent over to underlap the portion 8 as represented at 14.

The core 4, adjacent its upper edge, at 65 the portion thereof across which the clip 5 extends, is apertured as represented at 15, the end portion 6 of the clip being also apertured, as represented at 16, these apertures registering and affording an opening 70 through which the current-conducting wires represented at 17 may lead upwardly into, and through, the nipple 9 to the contacts (not shown) of the socket device 10. By 75 preference, the metal displaced from the clip portion 6 to form the opening 16, is 80 bent to extend through the opening 15 and overlap the front face of the core 4, as represented at 18, to form a durable lining 85 for the opening 15 and to insure the rigid connection of the clip 5 with the core, 90 against displacement thereon.

The particular device, shown as above 95 stated, is a Christmas wreath, the ornamental covering for the core 4 being shown as formed of decorative rope 19 wound spirally 100 about the core and over the clip 5 to conceal these parts, the engagement of the rope with the clip augmenting the strength of the structure. The candle tube 11 rests at its lower end upon the material 19 extending 105 directly therebeneath.

The construction shown in Fig. 4 comprises a core formed of two annular concavo-convex members represented at 20 and 110 of the same construction as the core 4 of the preceding figures, these members 20 being reversely disposed to form a core substantially circular in cross-section. The core is shown as wound with rope 21, like the rope 19, and the structure thus provided is 115 equipped with a clip 22 shown as formed of a band 23 encircling the sheathed core-structure with its ends received flatwise to-

gether by a nipple shown as formed of an internally-threaded tubular member 24 which extends through holes in the overlapped ends of the band 23, its lower end 5 carrying a nut 25 and its portion above the band provided with a collar 26 shown as containing a lateral opening 27 which registers with an opening (not shown) in the wall of the member 24 and opening into 10 the interior of the latter. The clip device 22 applied to the wreath structure in the portion shown, is secured thereon by drawing the ends of the band together to produce the desired encircling grip about the wreath 15 structure and in such condition, tightening the nut 25. The upper end of the member 24 is provided for attachment thereof of the electric socket (not shown) but as described of the structure of the preceding 20 figures, the current-conducting wires of the socket extending downwardly in the member 24 thence out through the opening in its side and through the opening 27 in the collar 26.

25 It will be manifest from the foregoing that whereas the clip device of Figs. 1, 2 and 3 is shown as directly connected with the core 4, it is within my invention to apply the clip to the structure after the rope 30 has been applied thereto the clip engaging the rope, as in the construction shown in Fig. 4. Also while the clip in Fig. 4 is shown as applied to the rope it may be applied directly to the core and the rope, 35 afterwards applied, in which case the rope would preferably overlap the clip.

It will also be understood that, if desired, the clips described may be formed of wire and when the clip is applied to the structure after the core is assembled with its 40 sheathing, the making of the clip of wire may be advantageous inasmuch as it would be less conspicuous than sheet metal.

It will be understood from the foregoing 45 that a device constructed in accordance with my invention is not only of simple, economical construction, but is also very durable and presents a highly ornamental effect.

While I have illustrated and described 50 certain particular constructions embodying my invention, I do not wish to be understood as intending to limit it thereto as the same may be variously modified and altered, and the invention otherwise embodied, without departing from the spirit thereof.

55 What I claim as new, and desire to secure by Letters Patent, is:

A device of the character set forth, comprising a core formed of sheet fibrous material in the form of an annulus of concavo-convex cross-section, a clip extending across the convex face of said core with its ends overlapping the rear side of said core, said 60 clip having a substantially flat upper portion, and a hollow nipple, for an electric-lamp socket, on said flat portion, said core and the upper end portion of said clip which 65 opposes the rear face of said core containing apertures substantially in registration with each other and with the opening in 70 said nipple.

MAX HERSKOVITZ.
